United States Patent Office

Des. 228,754
Patented Oct. 23, 1973

228,754

SNOWMOBILE

Joseph Mango, Midlothian, Ill., assignor to
AMF Incorporated

Continuation of abandoned design application Ser. No.
19,747, Oct. 27, 1969. This application Mar. 4, 1971,
Ser. No. 121,236

Term of patent 14 years

Int. Cl. D12—14

U.S. Cl. D14—24

FIG. I

FIG. 2

FIG. 1 is a perspective view of a snowmobile taken from the left front thereof.

FIG. 2 is a perspective view of a snowmobile taken from the left rear thereof.

The side opposite to the one shown is a mirror image thereof.

This application is a continuation of D. 19,747 filed Oct. 27, 1969, now abandoned.

I claim:

The ornamental design for a snowmobile, as shown.
